DEVICE FOR TEACHING THE TELLING OF TIME

Carroll E. Sand, Wheaton, Ill., assignor to Sears,
Roebuck and Co., Chicago, Ill.

Filed Mar. 15, 1972, Ser. No. 235,097

Term of patent 14 years

Int. Cl. D19—07

U.S. Cl. D25—1 R

FIG. 1

FIG. 2

FIG. 3

FIG. 4

FIG. 5

FIG. 1 is a perspective view of a device for teaching the telling of time showing my new design;

FIG. 2 is a top plan view thereof;

FIG. 3 is a bottom plan view;

FIG. 4 is a side elevational view taken on line 4—4 of FIG. 2; and

FIG. 5 is a side elevational view taken on line 5—5 of FIG. 3.

I claim:

The ornamental design for a device for teaching the telling of time, as shown and described.
